Primary Examiner — Thomas Johannes*Assistant Examiner* — Catherine Posthauer(57) **CLAIM**

The ornamental design for a safety cap, as shown and described.

DESCRIPTION

FIG. 1 is a perspective view of a safety cap according to the present invention;

FIG. 2 is a front view of the safety cap of FIG. 1, the rear, left, and right side views being a mirror image thereof;

FIG. 3 is a top plan view of the safety cap of FIG. 1; and, FIG. 4 is a bottom plan view of the safety cap of FIG. 1.

The broken lines are shown for the purpose of illustrating parts of the safety cap that form no part of the claimed design.
